UNITED STATES PATENT OFFICE.

JOHN C. BOWERS, OF BOSTON, MASSACHUSETTS.

CAN-SEALING MACHINE.

Specification of Letters Patent. Patented Apr. 20, 1915.

1,136,399.

Application filed September 7, 1912. Serial No. 719,099.

To all whom it may concern:

Be it known that I, JOHN C. BOWERS, of Boston, in the county of Suffolk and State of Massachusetts, a citizen of the United States, have invented new and useful Improvements in Can-Sealing Machines, of which the following is a specification.

In sealing metal cans such as sardine cans it is desirable to avoid the use of solder for various reasons and in Letters Patent of the United States issued to me October 1, 1907, No. 867,239, I have described and shown a hermetically sealed receptacle or can in which both the can and the cover have a flange, the cover being adapted to fit upon the can and the flanges being held together by a strip of metal bent into U shape and clamped upon the edges of the flanges.

My present invention relates to a machine wherein by the one operation a strip is bent and applied to the flanges. The essential features of such a machine are means for automatically feeding, bending, and cutting the strip, and means for delivering it to the sealing rolls and rolls for applying the strip to the flanges to seal the can, the can held in a mechanism which may be rotated so that the strip may be applied to the entire periphery of the can; and when this is done, if the pressure is sufficient, the can will be properly sealed whether the cover flange is of the exact form of the flange shown in the said Letters Patent, that is, with its edge bent over to form a shoulder, or whether the cover flange is left flat. In the present invention means are provided for performing these various operations and the several arrangements and parts will be understood by reference to the drawings.

I do not mean to limit myself to the arrangement hereinafter shown and described as the parts may be differently arranged and power applied to operate them in a different manner from that shown.

In the drawings:—Figure 1 is a plan of a machine embodying my invention. Fig. 2 is a section on line 2—2 of Fig. 1. Figs. 3, 4 and 5 are sections on lines 3—3, 4—4 and 5—5, respectively, of Fig. 2. Fig. 3^a is a detail of a portion of the mechanism of Fig. 3. Fig. 6 is a section on line 6—6 of Fig. 7, and Fig. 7 is a detail showing the mechanism for clamping the can in place and also

for clamping the upper sealing roll during the sealing operation, all the sections except Fig. 2 being very much enlarged.

A is a table on which the various parts are supported, A¹ being a platform on the table to receive the can holder against which the can is held under pressure and upon which the can holder is moved.

A² is a head for carrying the sealing mechanism.

B is a pulley connected by means of a clutch B¹, of any ordinary construction, with the shaft B². This shaft B² is supported under the table in a suitable hanger or bearing (not shown) and carries a pinion B³ which meshes with a gear B⁴ on the cam shaft B⁵. At the farther end of the cam shaft B⁵ is a gear B⁶ in mesh with a pinion B⁷ on the end of a counter-shaft B⁸ and connected thereto by a slip clutch. The shaft B⁸ carries various bevel gears to be described below.

The strip feeding and bending mechanism comprises a guide-way C having a slot therein adapted to receive a flat strip of metal which may be drawn from a coil or otherwise fed to the machine.

C¹, C² are feeding rolls. C¹ is mounted on a shaft C³ which passes down through the table and carries at its lower end a bevel gear C⁴ meshing with a bevel gear C⁵ on shaft B⁸. It also carries a pinion C⁶ which meshes with a pinion of corresponding size on the shaft C⁷ on which roll C² is mounted.

D, D¹ are forming rolls adapted to grip the strip and give it a V-shaped bend. For this purpose the roll D has an angular periphery (see Fig. 2) and the roll D¹ has a corresponding groove, the two fitting together and the strip being fed between them. The roll D is mounted on a shaft D² which passes down through the table and carries at its lower end a bevel gear D³ meshing with a corresponding gear D⁴ on the shaft B⁸. It carries a pinion D⁵ which meshes with a pinion of corresponding size on the shaft D⁶ on which roll D¹ is mounted.

A further forming operation is given to the strip by rolls E, E¹, the roll E having a somewhat U-shaped periphery (see Fig. 2) and cooperating with the roll E¹ which is grooved, the two fitting together as in the case of the rolls D, D¹, and giving the final

form to the strip. The roll E^1 is mounted on a shaft E^3 carrying a pinion corresponding in size with the pinion E^5 on the shaft E^2 which carries roll E and which passes 5 down through the table and carries at its lower end a bevel gear E^3 meshing with a corresponding bevel gear E^4 on the shaft B^8 . The operation of these rolls is alike and is carried on whenever the shaft B^8 is 10 rotated.

Between the rolls C^1 , C^2 and D , D^1 are guideways F , F^1 , and between the rolls D , D^1 and E , E^1 there is a guideway F^2 . The guideway F is shaped to conform to the 15 flatness of the strip and this is true also of the guideway F^1 . The guideway F^2 , however, is shaped to conform to the bend which has by that time been given the strip. Beyond the rolls E , E^1 there is also a carriage 20 F^3 which has a guideway in it which conforms to the shape which has been given to the strip by the rolls E , E^1 . A guideway F^4 suitably shaped extends from the front 25 of the carriage to a point close to the sealing rolls. It should be narrower from the point 30 f forward so as not to interfere with the movements of the can. The entrance to each 35 strip to the guideway itself, thus providing for any irregularity in the direction in which the end of the strip is moving and the guideways should be brought as close to the rolls as is practicable.

35 The carriage F^3 is mounted in a slideway F^5 and has a boss F^6 on its under side which projects through a slot in the table of sufficient length to allow it to have a suitable reciprocating movement. To this boss is attached a cam rod F^7 the lower end of which projects into a groove F^8 in the cam F^9 on shaft B^8 . By this means the carriage is reciprocated the parts being properly proportioned to steady its movements.

40 To cut the strip into suitable lengths I have provided a knife or cutter G which is mounted to slide crosswise the strip in ways G^1 . The end of this knife is L-shaped as shown in Fig. 2 so that it makes a tongue, 45 that is, the end of the strip is slightly narrower than the full width of the strip forming a narrow tongue which in the sealing operation overlaps the seal on the can as described in my said patent. This knife is 50 given its crosswise movement at the proper time by means of a cam G^2 on the shaft B^6 . This cam (see Fig. 4) has a slight projection or swell G^3 upon it which engages an angle lever G^4 pivoted at G^5 in a hanger G^6 projecting from the under side of the table and connected at its upper end by the connecting rod G^7 with the knife G . At the proper 55 moment the cam swell G^3 throws the lever G^4 which advances the knife G across the 60 path of the strip, thus cutting the strip, the 65

strip being suitably held for the purpose. The lever G^4 is held against the cam by the spring G^8 , one end of which is attached to the lever and the other end to the under side of the table as shown.

I have also shown at H grippers which are mounted on the carriage F^3 and grip the strip at the proper moment to feed it positively forward to the sealing rolls upon the movement of the carriage. These grippers are located one on each side of the carriage F^3 and project into the guideway in the carriage. They are constructed to yield slightly to any forward pull of the strip but as the carriage moves forward they grip the strip and pull it along as the carriage moves. The mechanism heretofore described therefore feeds, bends longitudinally, and cuts off a strip of metal of proper length to slightly more than surround the edge of the can which is to be sealed and feeds it to the sealing rolls.

The sealing operation is performed by means of two rolls the peripheries of which are suitably shaped, the lower roll J having a flat periphery, the upper roll J^1 having a periphery of two diameters, the part j resting upon the strip during the sealing operation and the part j^1 forming a stop or guide for the edge of the strip and running on the cover flange or otherwise according to whether the flange is flat or is shaped as in my said patent. To operate these rolls the shaft B^8 carries at its end a bevel gear J^2 which engages a corresponding bevel gear J^3 mounted on the shaft J^4 which carries at its outer end a gear J^5 which meshes with a gear J^6 on the end of the shaft J^7 which carries the lower roll J . In addition the shaft J^7 carries a pinion J^8 which meshes with a corresponding pinion J^9 on the shaft J^{10} which carries the upper roll J^1 . The shaft J^7 is mounted in two fixed bearings J^{11} and J^{12} in the head A^2 . The shaft J^{10} must be allowed a certain very slight rocking motion in order that the roll J^1 may be lifted slightly when it is to be placed upon the work. For this purpose the bearing J^{12} is pivoted by the pin or bolt J^{15} in its support and the bearing J^{14} is capable of a slight movement in its support.

In order to hold the roll J^1 down to its work the bearing J^{14} has mounted above it in the head A^2 a slide K to which is pivoted a toggle arm K^1 which is pivoted to an angle lever K^2 forming a second toggle arm connected by a connecting rod K^3 with a cam lever K^4 the farther end of which is pivoted in a hanger K^5 on the under side of the table. A cam K^6 provided with a suitable cam groove gives the rod K^3 and its angle lever K^2 movements at the proper time to release pressure from the roll J^1 and allow it to be lifted to allow a sealed can to be removed and an unsealed can to

be substituted. I prefer to provide a cushion k of rubber or the like between the lower end of the part K and the bearing J^4 for the shaft J^10 and, as shown, such cushion fits into a recess in the bottom of the part K and rests on a metal plate or face k^1 , on top of bearing J^4 , this block being held in place by means of a frame k^2 attached to the part K .

10 In order to hold the strip against the work I have shown a roll L mounted on a vertical pin L^1 in an adjustable frame L^2 supported on the head A^2 and adapted to be set up against it by screws I or in any other 15 desired way against yielding cushions I^1 so that the roll L will bear against the strip and hold it against the lateral edge or periphery of the flange of the box and cover to be sealed with a yielding pressure, so that 20 if necessary the roll L^1 may give slightly to conform to any irregularities in the movement of the box or can.

While other methods of holding the box or can in place may be used I have shown a 25 method which is particularly effective where the box is round although it answers with a box having rounded corners such as a sardine box.

The plate A^1 carries upon it a sliding bed 30 or can holder M which is hollowed to receive the bottom of the can N . In cans of this class the cover is usually dished, the cover being shown in this case in Fig. 7 at N^1 , the flange of the box being lettered n and 35 the flange of the cover being lettered n^1 .

To hold the cover in place during the sealing operation and also to serve as a guide to hold the various parts in place I have shown a form M^1 which is recessed to receive an anti-friction roll P . This form is of the same shape as the recess in the top of the cover and fits it closely. The roll P is free to turn on the lower end of a rod P^1 mounted in bearings P^2, P^3 projecting from 45 the head of the machine. The upper end of this rod P^1 is carried in the forked end of a lever P^4 pivoted to the top of the head and carrying at its other end a connecting rod P^5 which is connected to a cam lever 50 P^6 pivoted to a hanger P^7 under the table A . A cam roll carried by this lever runs in a suitable groove in the cam P^8 which cam is mounted on the shaft B^8 , so that upon the rotation of the shaft B^8 , from time to time 55 the rod P^1 is lifted so as to release the form.

In the operation of the machine as above described the parts are so proportioned and turned that the strip forming rolls and the sealing rolls, that is, those parts which are 60 operated by the shaft B^8 shall be in operation about $\frac{1}{2}$ of a revolution of the cam shaft B^8 , and be stationary during the other $\frac{1}{2}$. To accomplish this various means familiar to mechanics may be employed but 65 I have shown in Figs. 3 and 3^a mechanism

especially adapted for that purpose, and comprising the form of slip clutch above referred to.

On the end of shaft B^8 is a cam R on which rests a roll on one arm R^1 of a bent 70 lever pivoted to the frame r^1 . A roll r^2 on the other arm R^2 of this lever rests on the clutch disk R^3 splined to the shaft B^8 . The clutch disk R^3 (see Fig. 3) has a quill 75 r^3 on which runs the pinion B^7 . Washers r^4 of leather or the like separate the pinion B^7 from the disk R^3 and also from the nut r^5 which screws onto the quill which is threaded for the purpose and holds the parts together. This nut is set up sufficiently 80 tightly to cause the pinion B^7 to turn the disk R^3 and hence the shaft B^8 under ordinary conditions, but if the disk is restrained in its rotation the pinion will continue to rotate without turning the disk or shaft. 85

It will be noted that in Fig. 3 the roll r^2 rests in the recess r^6 in the disk R^3 and it will hold the disk at rest until the swell on cam R lifts the arm R^1 thus lifting the roll r^2 out of the recess r^6 and allowing the disk 90 and shaft B^8 to rotate with the pinion B^7 .

The operation of the machine is briefly as follows: A strip having been fed to the formers is shaped by them and when it has reached the extreme of the forward movement given to it by the feed rolls and forming rolls it is cut off and thereafter is fed farther by the carriage to its position against the edge of the can and cover flanges, the can and cover having been put in position 100 and under the roll J^1 which at this moment is free to be lifted. When the roll J^1 drops and is held down by the straightening of the toggle arms K^1, K^2 the friction of the sealing rolls is sufficient to cause the movement of 105 the can, the holder M sliding around on the plate A^1 , the sealing operation taking place at the same time. The recess in the form M^1 corresponding as it does in shape with the flanges, the inner side of its upwardly 110 projecting edge m serves with the roll P to guide the can in its passage so that the flanges and strip will always remain in proper relation to the sealing rolls J, J^1 . The parts are timed so that the can will 115 make slightly more than one revolution, say perhaps an inch, before the parts are released, this extra movement being sufficient to entirely surround the periphery of the flanger with the complete width of the strip, 120 the tongue of the strip projecting somewhat beyond the point of complete sealing, this construction being fully described in my patent above referred to.

The various cams are arranged to perform the necessary sequence of operations, the cam R being set to allow the slip clutch to engage the shaft B^8 and cause the feeding and sealing operations to take place simultaneously and the knife operates when the 130

feeding and sealing operations have stopped and during the period when the pressure on the can holder has been released and the can is being removed, the pressure on the pressure rolls being released at the same moment. As the can holder is free to be moved by hand at this moment, when the new can is put in place the can holder may be slipped around on the table to the point where it is bent to begin the sealing operation usually about the middle of one of the long sides.

I do not mean to limit my invention to the details of mechanism above described as in embodiments of my invention heretofore made under my direction other mechanisms have proved useful for accomplishing the same purpose.

What I claim as my invention is:

1. A box sealing machine comprising a rotatable work-holder, a strip-feeding mechanism, a strip-forming mechanism, and sealing rolls adapted to seal the strip upon the work.

2. A box-sealing machine comprising a rotatable work-holder, a strip-feeding mechanism, a strip-forming mechanism, and sealing rolls adapted to seal the strip upon the work, one of said rolls being mounted in a bearing, adapted to be rocked, and means for rocking said bearing.

3. A box-sealing machine comprising a rotatable work-holder, a strip-feeding mechanism, a strip-forming mechanism, means for holding the strip straight during the feeding and forming operations, and sealing rolls adapted to seal the strip upon the work.

4. A box-sealing machine comprising a rotatable work-holder, a strip-feeding mechanism, a strip-forming mechanism, sealing rolls adapted to seal the strip upon the work, and a guide adapted to hold the strip against the work during the sealing operation.

5. A box-sealing machine comprising a rotatable work-holder, a strip-feeding mechanism, a strip-forming mechanism, a strip-attaching mechanism, and means for cutting the strip.

6. A box-sealing machine comprising a rotatable work-holder, a strip-feeding mechanism, a strip-forming mechanism, a strip-attaching mechanism, and a cutting mechanism located to cut the strip between the strip-feeding mechanism and the strip-forming mechanism.

7. In a box sealing machine, a work-holder comprising two members adapted to clamp a box and its cover between them, means for forming a strip and means for simultaneously sealing a strip upon the edge of said box and cover in said work-holder and rotating said work-holder, box and cover.

8. In a box-sealing machine, a work-holder comprising two members adapted to clamp a box and its cover between them, and means for automatically separating the members of

said work-holder and allowing them to close on the work, in combination with means for applying the strip to the work while in said work-holder and simultaneously rotating said work-holder, said means comprising two parallel shafts and means whereby they are rotated, and two forming rolls, one mounted on each shaft and adapted to clamp the upper and under sides of said strip against the work, to seal the cover and box.

9. In a box-sealing machine, a work-holder comprising two members adapted to clamp a box and its cover between them, and means for automatically separating the members of said work-holder to release the work and for closing them together to clamp the work, in combination with sealing rolls adapted to apply a sealing strip to the flanges of the work and rotate the work, and means for releasing said sealing rolls coincidentally with the separation of the members of the work-holder.

10. In a box-sealing machine, two sealing rolls, a work-holder comprising two members and means adapted to hold a strip under said sealing rolls and against the work during the sealing operation, and means for separating the members of said work-holder, and means for releasing said sealing rolls.

11. In a box sealing machine, a work-holder, comprising two members, means for clamping the work between said members and for releasing the work, sealing rolls adapted to apply a sealing strip to said work and means for feeding a sealing strip thereto comprising feed rolls, forming rolls and means for giving said feeding and forming rolls an intermittent movement, and guides located to guide the strip from said forming rolls to the work, as described.

12. In a box-sealing machine, sealing rolls and means for feeding a sealing strip thereto comprising feed rolls, forming rolls and means for giving them an intermittent movement, and guides located to guide said strip from the forming rolls to the work, one of said guides having a reciprocating motion and means whereby it is reciprocated.

13. In a box-sealing machine, sealing rolls and means for rotating them, and a strip-feeding and forming mechanism adapted to feed a sealing strip to said sealing rolls, a rotatable work-holder adapted to feed the work between said sealing rolls, one of said sealing rolls having a flat periphery and the other roll having a periphery of two diameters, as and for the purposes set forth.

14. A machine for closing cans, comprising holding means constructed and arranged to grasp a can with its cover in place, such can and cover having outwardly projecting flanges lying closely together, a strip feed comprising a plurality of pairs of rolls adapted to grasp a flat strip and constructed

to indent and fold such strip about its longitudinal center line, means for advancing the strip until its forward end embraces the flanges of the can, and a sealing means arranged to bear on opposite sides of the flanges and means for giving said sealing means a positive motion whereby said can and said strip will be fed simultaneously and said strip will be bent around said can and its edge portions caused to embrace the flanges throughout their entire length.

15. A machine for placing a sealing strip upon flanges extending in close propinquity from the body and cover of a can, including a holder for the can, strip-placing mechanism including members arranged with respect to said holder to embrace the flanges and a strip and having a part to bear on that part of the strip which passes over the edges 20 of the flanges, and means for feeding a strip bent longitudinally into U-form upon the flanges and between said members at the same time.

16. A machine for hermetically sealing cans, boxes and the like having overlapping flanges comprising a rotatable holder for supporting a can of this character, means for folding a strip into U-form in cross-section, and placing said strip so that its edges 30 may embrace the flanges of the can, squeezing mechanism for exerting a rolling pressure on the strip upon the opposite sides of said flanges, and causing the pressure of said squeezing mechanism to be applied at all 35 points throughout the extent of the flanges.

17. A machine for hermetically sealing cans, boxes and the like having overlapping flanges comprising means for feeding into the machine a flat strip, means for bending such strip into U-form in cross section, severing means constructed to cut off a length of the strip having a projecting tongue and arranged so that the length thus severed may be sufficient to encompass the can and 40 overlap at the ends, a rotatable holder for the can, and clamping means for pressing the edges of the strip against the opposite faces of the flanges of the can throughout the entire extent thereof.

50. 18. A machine for hermetically sealing by mechanical means a can having adjacent flanges on its body and the periphery of its cover, comprising a holder for the article to be sealed, strip feeding and folding means 55 constructed to bend a strip about a longitudinal line and place such strip with its sides embracing the flanges of the can, strip-setting means for placing said strip upon the can and cover flanges, and means for 60 giving said setting means and can holder relative movements such as to bend the strip around the periphery of the flanges and cause it to embrace the latter throughout their entire extent.

65. 19. A machine for hermetically sealing by

mechanical means a can having adjacent flanges on its body and cover, comprising a rotatable holder for the article to be sealed, strip-feeding and folding means constructed to bend a strip transversely about a longitudinal line and place such strip with its sides embracing the flanges of the can, strip-setting means for clamping said strip upon the can flanges, means for imparting relative movement to said setting means and rotatable holder constructed and arranged to continue such relative movement through more than the entire circuit of the can to cause the clamping pressure of the setting means to be applied to all parts of the can 70 flanges and strip throughout more than the entire extent of the flanges, whereby an overlapping end of the strip may be set.

20. A machine for hermetically sealing by mechanical means a can having adjacent flanges on its body and cover, comprising a rotatable holder for the article to be sealed, a strip-feeding and folding means constructed to bend a strip transversely about a longitudinal line and place such strip with 80 its sides embracing the flanges of the can, strip-setting means for clamping said strip upon the can flanges, said strip setting mechanism being adapted to give said rotatable holder a rotary movement greater than its peripheral length whereby to set an overlapping end of the strip.

21. An organized automatic machine for applying a sealing strip to the overlapping projecting edges of a can body and cover, comprising a rotatable can holder, feeding mechanism arranged to advance and guide a strip, folded longitudinally in U-form, until its forward end is placed on and embraces said edges, a pair of coöperating pressure members arranged to bear on the opposite sides of the strip when so placed, means for releasing said members whereby the strip and edges may be placed between them, and thereafter forcing the members together to grip the strip and edges with a severe and yielding pressure, and means for rotating said pressure members whereby said can and cover will be rotated and the entire extent of the strip and edges will be 100 acted upon by said members.

22. In a can sealing machine, in combination with a rotatable holder for the cans to be sealed and clamping means for securing a sealing strip about said cans, mechanism for forming a sealing strip comprising a series of rolls constructed to feed a strip in the form of flat ribbon or tape and form a longitudinal indentation approximately in the center thereof, said rolls being arranged to feed the strip toward the can, and also formed so as progressively to deepen the indentation and draw the sides of strip nearer together, giving the strip a U-form in cross-section.

23. In a can sealing machine, in combination with a holder for the cans to be sealed and clamping means for securing a sealing strip about said cans, mechanism for forming a sealing strip comprising a series of benders constructed to form a longitudinal groove or indentation between the edges of a strip and to progressively deepen such indentation and bring the sides of the strip nearer together into U-form in cross-section, and means for feeding the strip to the can.
24. In a can sealing machine, in combination with a holder for the cans to be sealed and clamping means for securing a sealing strip about said cans, mechanism for forming a sealing strip comprising a series of benders constructed to form a longitudinal groove or indentation between the edges of a strip and to progressively deepen such indentation and bend the sides further toward one another until such sides on each side of the bend are approximately parallel, and bring the sides of the strip nearer together, said benders being located in such position that a strip delivered therefrom is fed to the clamping means into position to embrace by its edges the sealing flanges of the can.
25. In a can sealing machine, in combination with a rotatable holder for the cans to be sealed and means for placing a sealing strip upon adjacent flanges of the body and cover of the can and for bending the strip around the periphery of such flanges, mechanism for forming a sealing strip and delivering such strip to said means comprising a series of complementary bending and feeding rolls arranged in series with the last rolls of the series arranged adjacent to said means, the first rolls of said series consisting of a roll having an approximately V-shaped rib and a complementary roll having a correspondingly shaped groove, and the subsequent rolls having a coöperating U-shaped rib and groove, whereby a flat strip is progressively folded into U-shape in cross section.
26. A machine for hermetically sealing cans, boxes, and the like, having overlapping flanges comprising means for feeding into the machine a flat strip, means for bending such strip about its longitudinal center into U-form in cross-section, severing means constructed to cut off a length of the strip having a projecting tongue and arranged so that the length thus severed may be sufficient to encompass the can and overlap at the ends, a holder for the can and clamping means for pressing the edges of the strip against the opposite faces of the flanges of the can throughout the entire extent thereof.
27. A machine for hermetically sealing by mechanical means a can having adjacent flanges on its body and the periphery of its cover, comprising a holder for the article to be sealed, strip feeding and folding means constructed to bend a strip about its longitudinal center and place such strip with its sides embracing the flanges of the can, strip-setting means for placing said strip upon the can and cover flanges, and means for giving said setting means and can holder relative movements such as to bend the strip around the periphery of the flanges and cause it to embrace the latter throughout their entire extent.
28. A machine for hermetically sealing by mechanical means a can having adjacent flanges on its body and cover, comprising a holder for the article to be sealed, strip-feeding and folding means constructed to bend a strip transversely about its longitudinal center and place such strip with its sides embracing the flanges of the can, strip-setting means for clamping said strip upon the can flanges, feeding means for imparting relative movements to said setting means and holder, constructed and arranged to continue such relative movement through more than the entire circuit of the can, whereby to cause the clamping pressure of the setting means to be applied to all parts of the can flanges and strip throughout more than the entire extent of the flanges, whereby an overlapping end of the strip may be set.
29. A machine for attaching the cover to a can having adjacent flanges on its body and cover, by means of a lengthwise-doubled sealing strip comprising a holder for the article to be sealed, strip-feeding and folding means constructed to bend a strip transversely about its longitudinal center and place such strip with its sides embracing the flanges of the can, strip-setting means for progressively applying said strip upon the can flanges, including provisions for causing said applying means to exert a yielding uniform pressure and permitting the same to accommodate irregularities in thickness of the strip and flanges, and means for giving said setting means and can holder relative movements such as to apply the clamping pressure throughout the entire extent of the can flanges.
30. In a can-sealing machine, in combination with a holder for the cans to be sealed and clamping means for securing a sealing strip about said cans, mechanism for forming a sealing strip and for feeding the strip to the clamping means comprising a series of benders constructed to form a longitudinal groove or indentation between the edges of a strip and to progressively deepen such indentation and bring the sides of the strip nearer together into U-form in cross-section.
31. A machine for hermetically sealing cans, boxes and the like having overlapping flanges comprising a holder for supporting a can of this character, means for folding a

strip about its longitudinal center into U-form in cross-section, and placing said strip so that its edges may embrace the flanges of the can, squeezing mechanism for exerting 5 a rolling pressure on the strip upon the opposite sides of said flanges, and feeding mechanism for causing the pressure of said

squeezing mechanism to be applied at all points throughout the extent of the flanges.
